CLAIM

The ornamental design for a mobile phone, as shown and described.

DESCRIPTION

1. Mobile phone

1.1 : Perspective

1.2 : Front

1.3 : Back

1.4 : Left

1.5 : Right

1.6 : Top

1.7 : Bottom

1.8 : Reference view, folded condition

1.9 : Reference view 2, folded condition

The broken lines depict portions of the mobile phone that form no part of the claimed design; reproduction 1.1 is a front perspective view of the mobile phone; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; reproduction 1.8 is a reference view showing the mobile phone folded in half; reproduction 1.9 is a reference view showing the mobile phone folded in half and displaying information on the front part; this is a design for a mobile phone with a flexible display which can be folded in half.
